UNITED STATES PATENT OFFICE.

BENJAMIN GALLSWORTHY, OF PORT ARTHUR, TEXAS.

STILL.

1,234,327.

Specification of Letters Patent. Patented July 24, 1917.

Application filed April 12, 1915. Serial No. 20,664.

To all whom it may concern:

Be it known that I, BENJAMIN GALLSWORTHY, a subject of the King of Great Britain, residing at Port Arthur, in the 5 county of Jefferson and State of Texas, have invented certain new and useful Improvement in Stills, of which the following is a specification.

This invention relates to new and useful 10 improvements in a still, and particularly in a still designed to be used for distilling petroleum or its products.

The object of the invention is to provide a still of the character described for 15 removing water and the volatile constituents from heavy crude oil, in the manufacture of refined oil or in the preparation of said constituents for distillation in the ordinary manner. The type of still hereinafter 20 described will bring the oil into contact with a uniform heat and provides for the relief of any suddenly formed vapors, which would cause the oil to boil over in stills now in common use.

25 With the above and other objects in view, the invention has particular relation to certain novel features of construction, operation and arrangement of parts, an example of which is given in this specification and 30 illustrated in the accompanying drawings, wherein:

Figure 1, is a vertical sectional view of the still.

Fig. 2, is a transverse sectional view, showing 35 the feeding coil employed, and,

Figs. 3 and 4, show plan views of the transverse plates or partitions employed.

Referring now more particularly to the drawings, wherein like numerals of reference designate similar parts in each of the figures, the numeral 1, refers to a cylindrical casing, preferably formed of sheet metal, which is surrounded by a covering 2, formed of asbestos or some similar material, provided for the purpose of retaining the heat and guarding against sudden changes of 45 temperature, and the casing is provided with a dome 3, having diaphragms, as 4, projecting inwardly from opposite sides thereof and whose free edges overlap, so as to prevent the fluid spray from being carried into the vapor line 5, which is controlled by the valve 6, and which leads to a suitable condenser, (not shown).

50 A coil 7, whose under side is provided

with a double row of perforations 8, is arranged in the upper portion of the still and communicates with the inlet pipe 9, which is controlled by the valve 10, and which leads from the suitable feed tank or pump. A 60 steam line 11, controlled by the valve 12 enters the still near the bottom and terminates in a coil 13, within the still, the upper side of said coil being provided with a double row of perforations. The steam line 11, 65 is connected with a suitable superheater, (not shown). Leading from the bottom of the still is the discharge pipe 14, controlled by the valve 15, and through which residual oil is discharged from the still into a suitable 70 receiving tank, (not shown), and a drain pipe 16, controlled by the valve 17, also leads from the bottom of the still, through which surplus water, formed in the still while heating up preparatory to distillation proper, 75 may be drained off.

Between the coils 7 and 13, and secured to the casing wall is a series of projections 18, which are fixed to said wall and are spaced a uniform distance apart there-around, the projections of each series being in transverse alinement and the series being spaced the required distance apart vertically. Each series of projections supports a transverse plate or partition, as 19, and 20. These 85 partitions are perforated, the partitions 19, having annular rows of perforations, as 21, cut near the edge, and the central portion of the partitions 20, having the perforations 22, the perforations of each plate being 90 cut of vertical alinement with those of the immediately succeeding plates above and below, so that the superheated steam delivered through the coil 13, will pass up in a devious course through the series of partitions. The partitions have peripheral notches, as 23, and in placing any particular partition in position on any particular series of projections 18, the partition is turned, so 95 that the projections above said series will 100 pass through said notches and said partition is then turned, so as to rest upon the desired projection as shown in Fig. 3, to which it is secured and the notches are then closed by means of plates, as 24, which are secured 105 to the partition, as is also shown in Fig. 3.

The oil to be treated is admitted through the pipe 9, by opening the valve 10, but not until after the still has been heated by the admission of super-heated steam from the 119

coil 13, and the condensed water which may have formed has been drained off through the pipe 16.

A steady stream of oil is kept running through the coil 7, the valve 6, being partially closed, so as to create a slight pressure in the still. The oil will gradually trickle down through the perforated partitions 19 and 20, and will be heated by the steam passing upwardly therethrough and the volatile portion will be separated from the residual oil and will pass up through the dome and out through the line 5, to the condenser. The amount of residual oil which collects in the bottom of the still, will be indicated by the glass gage 25, and the amount of pressure in the still will be indicated by the pressure gage 26. When the residual oil begins to show in the gage 25, it may be drawn off through the discharge pipe 14.

Leading from the side of the still between the partitions 19 and 20, are the gage cocks 27, by means of which the condition of the oil in the still may be ascertained and near the bottom of the still is a thermometer 28, to indicate the degree of heat of the oil within the still.

I have shown only one form of this device, but it is obvious that the mechanical structure thereof may be varied without departing from the principle of the invention and I hereby reserve the right to make such mechanical modifications, as may be found de-

sirable so long as I keep within the scope of the appended claim. 35

What I claim is:

A device of the character described including a receptacle having a dome, a coiled nozzle provided with a plurality of discharge perforations arranged at the top and bottom respectively, of the receptacle, oil and steam inlets communicating with the respective nozzles, a plurality of partitions arranged between said nozzles and spaced apart and dividing the receptacle into separate compartments, some of said partitions having a plurality of central perforations and the others having a plurality of marginal perforations arranged in annular rows, the first mentioned alternating with those last mentioned, gage cocks communicating with the respective compartments between said partitions, diaphragms projecting inwardly from opposite sides of the dome and arranged in staggered relation, a vapor line leading from said dome and a discharge pipe and a drain pipe leading from the bottom thereof.

In testimony whereof I have signed my name to this specification in the presence of two subscribing witnesses.

BENJAMIN GALLSWORTHY.
